UNITED STATES PATENT OFFICE.

ALBERT K. BODENHORN, OF SOUTHGATE, CALIFORNIA.

BURGLAR ALARM.

Application filed March 18, 1924. Serial No. 700,044.

To all whom it may concern:

Be it known that I, ALBERT K. BODENHORN, a citizen of the United States, residing at Southgate, in the county of Los Angeles and State of California, have invented new and useful Improvements in Burglar Alarms, of which the following is a specification.

This invention relates to burglar alarms, and it has for one of its objects the provision of a burglar alarm embodying gun mechanism.

With the foregoing objects in view, together with such other objects and advantages as may subsequently appear, this invention resides in the construction and arrangement of parts hereinafter described and claimed and illustrated in the accompanying drawings, in which:

20 Figure 1 is a vertical transverse section of the lower part of a window frame and the subjacent portion of a wall and showing one form of my burglar alarm, partly in section, associated with the window frame 25 and the wall;

Fig. 2 is a view similar to Fig. 1, showing the window in slightly raised position and the resulting effect on the mechanism of the burglar alarm;

30 Fig. 3 is a view taken on the lines 3—3 of Figs. 1 and 2;

Fig. 4 is a section taken on the line 4—4 of Fig. 1;

Fig. 5 is a section taken on the line 5—5 of Fig. 2;

Fig. 6 is a view showing the hammer of the gun;

Fig. 7 is a perspective view of means for extracting a cartridge from the gun;

40 Fig. 8 is a fragmentary view in elevation of a door and its jamb with my burglar alarm set, the door being closed;

Fig. 9 is a cross section taken on the line 9—9 of Fig. 8;

45 Fig. 10 is a view similar to Fig. 8, but showing the door slightly opened and the resulting effect on part of the mechanism of the alarm;

Fig. 11 is a cross section taken on the line 50 11—11 of Fig. 10;

Fig. 12 is a section taken on the line 12—12 of Fig. 8; and

Fig. 13 is a section taken on the line 13—13 of Fig. 8.

55 Referring to the drawings for a more detailed description thereof, and particularly

at first to Figs. 1 and 2, the numeral 20 indicates the lower portion of a window pane which is set in the lower sash 21. The numeral 22 indicates the window sill and 23 60 indicates a wall under the window sill, 24 being a floor. The lower sash 21 is provided with a vertical recess 25 positioned medially its inner side 26 and its outer side 27 and adapted to receive the upper portion 65 of a rod 28 having a boss 29. A horizontal recess 30 is also formed in the member 21 of the lower sash and extends from the inner face 26 to meet the recess 25. The recess 30 is enlarged at its inner portion, as 70 shown at 31 in Figs. 1, 2 and 5, and is adapted to receive a member 32 having a knob 33 extending beyond the inner face 26 and having a fork 34 at its inner end.

The fork 34 comprises two arcuate prongs 75 34^a and 34^b respectively which are resilient and normally engage the portion of the rod 28 adjacent the boss 29. The prongs 34^a and 34^b are provided respectively with outwardly curved lips 34^c and 34^d, the distance 80 between which is normally less than the diameter of the rod 28. A finishing plate 35 is secured to the face 26 of the member 21 and encircles the member 32. The rod 28 extends through an aperture 37 formed in 85 the window sill 22, through a portion of the wall 23, and through an aperture 39 formed in a tube 40, which is positioned transversely in the wall 23, and extends from the inner face 23^a of the wall to the outer face 23^b. The tube 40 has its outer portion 40^a reduced in diameter so that a shoulder 40^b is formed. The inner and larger portion 40^b of the tube 40 is formed with a longitudinal recess 42 in its lower 90 portion, the recess being clearly shown in Fig. 4.

The recess 42 slidably receives the elongated portion 43^a of a cartridge extractor 44 (shown in Fig. 7) which comprises a 100 flat ring 45 positioned at an end of the portion 43 and at right angles thereto. The portion 43 of the cartridge extractor 44 extends beyond the inner face 23^a of the wall 23, and the ring 45 of the extractor abuts 105 against the shoulder 40^b of the tube 40. A cartridge 46, which may be either blank or loaded, is placed within the tube 40, the flange 46^a of the cartridge abutting against the ring 45 of the extractor 44. A hammer 110 47 is positioned partly within the section 40^b of the tube 40 and extends beyond the

inner face 23^a of the wall 23. The hammer 47 comprises a knob 48 and a peripheral flange 49, the latter being positioned near the inner end of the hammer. A coil compression spring 50 encircles the hammer 47 and is held between the flange 49 and a plate 51 which is removably affixed to the inner face 23^a of the wall 23 and through which the hammer 47 extends. The plate 51 is provided with a slot 52, through which the portion 43 of the shell extractor 44 extends, the slot 52 being arcuate and of greater length than the width of the member 43. The plate 51, as shown in Fig. 3, is provided with opposing lugs 53 and 54 having formed therein respectively slots 55 and 56, these slots being formed in opposite sides of the lugs. The slots 55 and 56 engage respectively screws 57 and 58 which are secured to the wall 23.

It will be understood that by forming the plate 51, as described, the same may be readily removed from the wall by turning it through a small arc, so that the tube 40 may be opened for the purpose of removing a cartridge and inserting another cartridge therein. When the burglar alarm is set, the fork 34 engages the rod 28 immediately under the boss 29, which is wider than the distance between the prongs 34^a and 34^b of the fork, and the hammer 47 is drawn back, compressing the spring 50, the lower end of the rod 28 abutting against a face of the flange 49 to retain the hammer in retracted position and the spring compressed.

It will thus be seen that when an attempt is made to enter a building by raising the window, as shown in Fig. 2, the fork 34, which rises with the opening of the window, lifts the rod 28 out of the tube 40, so that the hammer 47 is caused by the action of the spring 50 to strike the cartridge 46, which is thereby fired, and, if blank, merely gives an alarm. After a cartridge has been used, it may be extracted after removing the plate 51 and the hammer 47 with the spring 50, by pulling the cartridge extractor 44.

At such times when it is not desired to have the burglar alarm set, the fork 34 may be made to disengage the rod 28 by pulling the knob 33 of the member 32 so that the fork 34 is pulled into the portion 31 of the recess 30. It will be understood that the window may then be raised without firing the cartridge, as the rod 28 will be retained in the tube 40.

Referring now to Figs. 8 to 13 inclusive, the numeral 65 indicates a door and the numeral 66 indicates the jamb for the door. In this modification, the tube 40, the shell extractor 44, the cartridge 46, the hammer 47, the spring 50 and the plate 51 are constructed and positioned as previously described, except that the tube 40 does not contain the aperture 39 as described for the first modi-

fication, and the hammer 47 is provided, in this modification, with a recess 68, the parts enumerated being fitted, in this instance, through the door jam and the adjacent wall. When the alarm of this modification is set, a member 69, pivoted on a screw 70, engages the recess 68 and contacts with the angular face 71 of an extension 72 projecting outwardly from a member 73 secured to the door 65 near the edge of the latter. When an attempt is made to open the door 65, it will be seen that the member 69 will slide upwardly on the face 71 of the extension 72 in the direction shown by the arrow 75 in Fig. 8, whereby the member 69 will be disengaged from the recess 68 in the hammer 47. This action causes the hammer to be released and to be projected against the cartridge 46, firing the same.

While I have herein described two forms of my invention, modifications thereof may be devised without departing from the spirit thereof, and it is to be understood that such modifications come within the scope of this invention.

What is claimed is:

1. A burglar alarm adapted to be associated with a wall and with a closure for an opening, said alarm comprising a tube extending through the wall, a cartridge retainable within said tube, a hammer within said tube, said hammer being adapted to strike said cartridge to fire the same, a coiled spring encircling said hammer, means associated with the closure for keeping said hammer in retracted position and said spring compressed when the closure is closed, said means being adapted to be actuated by the opening of the closure to release said hammer for impact against said cartridge, said hammer being urged against said cartridge by the expansion of said spring, and means for extracting said cartridge, and means comprising a slotted face plate for permitting said hammer and said cartridge to be withdrawn from said tube.

2. A burglar alarm adapted to be associated with a wall and with a closure for an opening, said alarm comprising a tube extending through the wall, a cartridge retainable within said tube, a hammer within said tube, said hammer being adapted to strike said cartridge to fire the same, a coiled spring encircling said hammer, means associated with the closure for keeping said hammer in retracted position and said spring compressed when the closure is closed, said means being adapted to be actuated by the opening of the closure to release said hammer for impact against said cartridge, said hammer being urged against said cartridge by the expansion of said spring, means for extracting said cartridge, and means positioned on the inner face of the wall for normally closing one end of said tube, said clos-

ing means being adapted to be readily detached to allow the removal of said cartridge and said hammer.

3. A burglar alarm adapted to be associated with a wall and with a closure for an opening, said alarm comprising a tube extending through the wall, a cartridge retainable within said tube, a hammer within said tube, said hammer being adapted to strike said cartridge to fire the same, a coiled spring encircling said hammer, means associated with the closure for keeping said hammer in retracted position and said spring compressed when the closure is closed, 10 said means being adapted to be actuated by the opening of the closure to release said hammer for impact against said cartridge, said hammer being urged against said cartridge by the expansion of said spring, 15 means for extracting said cartridge, and means positioned on the inner face of the wall for normally closing one end of said tube, said closing means being adapted to be readily detached to allow the removal of said cartridge.

4. A burglar alarm adapted to be associated with a wall and a closure for an opening, said alarm comprising a tube extending through the wall, a cartridge retainable within said tube, a hammer within said tube, said hammer being adapted to strike said cartridge to fire the same, means associated with the closure and with said hammer for keeping said hammer in retracted position when the closure is closed, 20 said means being adapted to be actuated by the opening of the closure to release said hammer for impact against said cartridge, means for extracting said cartridge, and comprising a plate and means for fastening the plate, said fastening means engaging slots in the plate, the slots being arranged to be disengaged from said fastening means by a turning of said plate. 25

5. A burglar alarm adapted to be associated with a wall and a closure for an opening, said alarm comprising a tube extending through the wall, a cartridge retainable within said tube, a hammer within said tube, said hammer being adapted to strike said cartridge to fire the same, actuating means associated with the closure and with said hammer for keeping said hammer in retracted position when the closure is closed, 30 said actuating means extending into the body of the closure being adapted to be actuated by the opening of the closure to release said hammer for impact against said cartridge, and means for releasing said actuated means. 45

6. A burglar alarm adapted to be associated with a wall and a closure for an opening, said alarm comprising a tube extending through the wall, a cartridge retainable within said tube, a hammer within said tube, said hammer being adapted to strike said cartridge to fire the same, means

associated with the closure and with said hammer for keeping said hammer in retracted position when the closure is closed, 55 said means being adapted to be actuated by the opening of the closure to release said hammer for impact against said cartridge, means for extracting said cartridge, and means positioned on the inner face of the wall for normally closing one end of said tube, said closing means being adapted to be readily detached to allow the removal of said cartridge.

7. A burglar alarm adapted to be associated with a wall and a closure for an opening, said alarm comprising a tube extending through the wall, a cartridge retainable within said tube, a hammer within said tube, said hammer being adapted to strike said cartridge to fire the same, means associated with the closure and with said hammer for keeping said hammer in retracted position when the closure is closed, 60 said means being adapted to be actuated by the opening of the closure to release said hammer for impact against said cartridge, means for extracting said cartridge, and comprising a plate and means for fastening the plate, said fastening means engaging 65 slots in the plate, the slots being arranged to be disengaged from said fastening means by a turning of said plate.

8. A burglar alarm comprising a tube having an enlarged end and a reduced end, 70 said reduced end being adapted to retain a cartridge therein adjacent the enlarged end, a cover plate for the enlarged end, a hammer 75 slideable through said cover plate into said enlarged end, a spring disposed within said enlarged end about said hammer, so as to urge said hammer to strike said cartridge, means for holding said hammer in retracted position, said means being associated with a closure, whereby opening movement of the closure will cause said means to release said hammer so as to strike the cartridge, said 80 cover plate being removably positioned over the enlarged end, and a cartridge extractor 85 extending through said cover plate and into 90 said enlarged end.

In testimony whereof I have signed my name to this specification.

ALBERT K. BODENHORN.
